(57) **CLAIM**

I claim the ornamental design for magnetic fastener, as shown and described.

DESCRIPTION

FIG. 1 is a perspective view, showing two magnetic fasteners, each one in accordance with my new design, shown with their upper and lower parts fastened together, in the context of a sandal illustrated in phantom outline, which sandal forms no part of the claimed design;

FIG. 2 is a perspective view of an upper part of a magnetic fastener in accordance with my new design;

FIG. 3 is a perspective view of a lower part of a magnetic fastener in accordance with my new design;

FIG. 4 is a perspective view of the upper part and the lower part of the magnetic fastener as shown in FIGS. 2 and 3, with the upper and lower parts positioned together for fastening together;

FIG. 5 is a top plan view of the upper part of the magnetic fastener in accordance with my new design;

FIG. 6 is a bottom plan view thereof;

FIG. 7 is a side elevation view thereof;

FIG. 8 is a front end elevation view thereof;

FIG. 9 is a rear end elevation view thereof

FIG. 10 is a top plan view of the lower part of the magnetic fastener in accordance with my new design;

FIG. 11 is a bottom plan view thereof; and,
